UNITED STATES PATENT OFFICE.

AUGUST E. KUTSCHBACH, OF HOUSTON, TEXAS.

PUMP.

1,225,041.

Specification of Letters Patent.

Patented May 8, 1917.

Application filed April 26, 1916. Serial No. 94,242.

To all whom it may concern:

Be it known that I, AUGUST E. KUTSCHBACH, a citizen of the United States, residing at Houston, in the county of Harris and State of Texas, have invented certain new and useful Improvements in Pumps, of which the following is a specification.

This invention relates to new and useful improvements in a pump.

10 The object of the invention is to provide a pump of the character described adapted to be used in oil or water wells for pumping out the sand and slush after the well has been completed and the chief feature of the 15 pump consists of the provision of means whereby water will be driven through the valve cage and against the valve seat and will keep said cage and seat free from sand. In pumps now in common use for this purpose, the sand and other detritus is disposed to collect in the valve cage and clog the valve and prevent it from working, and to obviate this defect the pump herein described has been provided.

25 With the above and other objects in view the invention has particular relation to certain novel features of construction, operation and arrangement of parts, an example of which is given in this specification and 30 illustrated in the accompanying drawings, wherein:

Figure 1 is a fragmentary vertical sectional view of the upper part of the pump,

Fig. 2 is a fragmentary vertical sectional 35 view of the lower part thereof and

Fig. 3 is a transverse sectional view taken on the line *a—a* of Fig. 1.

Referring now more particularly to the drawings, the numeral 1 designates the 40 pump barrel, which is attached at its upper end to the lower end of the pipe 2, which extends up through the bore to the surface. The lower end of the barrel is contracted slightly, as at 4, and a correspondingly tapered valve seat 5 is fitted therein having the opening 6 therethrough, which is controlled by the ball valve 7. Surrounding this seat is a flexible washer 8, which rests against the pump barrel and prevents leak- 45 age and upstanding from the seat 5 is a cage 9 provided to retain the valve in position. In the upper part of the barrel is a hollow plunger 10, whose upper end is 50 formed into a seat 11, having the passage-

way 12 therethrough, which is controlled 55 by the ball valve 13, retained in position by the valve cage 14, whose head 15 has the upstanding outwardly threaded tubular nipple 16, whereon the lower end of the tubular plunger rod 17 is threaded. The plunger is 60 provided with a plurality of cup-shaped washers 18, of well known construction, to prevent leakage therearound. The lower end of the plunger is internally threaded as at 19 to receive the externally threaded 65 neck 20, which upstands from the head of the cage 9. When it is desired to withdraw the seat 5, the plunger may be lowered and screwed on to the neck 20 and the plunger and seat may then be withdrawn together. 70 A pair of small pipes, as 21, 21, are provided, whose upper ends communicate with the interior of the barrel at its upper end and whose lower ends communicate with the interior of the barrel just above the 75 seat 5. Within the bore is the ordinary well casing 22, somewhat larger in diameter than the pump barrel and whose lower end carries the well screen 23, provided with openings to permit the inflow of the fluid. 80 Attached to the lower end of the barrel is a short perforated pipe section 24, whose lower end is plugged up and rests upon the bottom of the bore to sustain the pump 85 while in action, although this pipe section is not indispensable to the operation of the pump. The plunger rod 17 is actuated by a suitable motive power from the surface of the ground and, by this means the plunger is reciprocated up and down. As the plunger 90 moves upwardly, the valve 13 is seated and the valve 7 lifted, permitting the barrel to fill with fluid and lifting the fluid above the plunger and forcing it to the surface. 95 When the plunger is lowered the valve 7 is seated and the valve 13 lifted, permitting the fluid to pass above the plunger. Pure water may be forced from the surface through the plunger rod 17 down into the cage 14, which will keep said cage and the 100 valve therein freed from sand and the like which would otherwise collect thereon. This water is also forced through the pipes 21, 21 and discharged into the cage 9, thereby freeing said cage and the valve therein 105 from sand as above explained.

Upon the up stroke of the plunger a certain amount of fluid will pass from the bar-

rel through the pipes 21, 21, and be discharged against the cage 9 and will operate to cleanse said cage and valve.

What I claim is:

- 5 A pump including a barrel, a valve controlling the inflow of fluid into one end thereof, a plunger having a fluid passageway therethrough arranged to reciprocate in the barrel, a valve controlling said passageway, a hollow plunger rod connected to and provided to reciprocate said plunger through which fluid may be discharged

against said valve and a fluid conduit communicating at its respective ends with the interior of said barrel on opposite sides of 15 said plunger, and through which fluid may be driven against the barrel seat.

In testimony whereof I have signed my name to this specification in the presence of two subscribing witnesses.

AUGUST E. KUTSCHBACH.

Witnesses:
ANNIE L. CARY,
RUBY GLAZNER.
